(57) **CLAIM**

The ornamental design for a portable, collapsible traffic information display, as shown and described.

DESCRIPTION

FIG. 1 is an upper right perspective of the portable, collapsible traffic information display showing my new design:

FIG. 2 is a front plan view thereof;

FIG. 3 is a rear plan view thereof;

FIG. 4 is a right plan view, the left plan view being a mirror image thereof;

FIG. 5 is a top plan view thereof;

FIG. 6 is a bottom plan view thereof;

FIG. 7 is a front plan view of a second embodiment thereof, the sides, top and bottom appearing substantially the same as FIGS. 3-6 except for the sign wordage;

FIG. 8 is a front plan view of a third embodiment thereof, the sides, top and bottom appearing substantially the same as FIGS. 3-6 except for the sign wordage;

FIG. 9 is a front plan view of a fourth embodiment thereof, the sides, top and bottom appearing substantially the same as FIGS. 3-6 except for the sign wordage; and,

FIG. 10 is a front plan view of a fifth embodiment thereof, the sides, top and bottom appearing substantially the same as FIGS. 3-6 except for the sign wordage.
